UNITED STATES PATENT OFFICE.

SIM C. LAWLOR, OF DULUTH, MINNESOTA, ASSIGNOR OF THREE-FOURTHS
TO S. GEORGE STEVENS, TIMOTHY W. LEMIEUX, AND WALLACE E. HAR-
VEY, OF SAME PLACE.

PORTABLE BURGLAR-ALARM.

SPECIFICATION forming part of Letters Patent No. 517,869, dated April 10, 1894.

Application filed April 13, 1893. Serial No. 470,191. (No model.)

To all whom it may concern:

Be it known that I, SIM C. LAWLOR, a citizen of the United States, residing at Duluth, in the county of St. Louis and State of Minnesota, have invented certain new and useful Improvements in a Combined Portable Burglar-Alarm and Lock; and I do hereby declare the following to be a full, clear, and exact description of the invention, which will enable others skilled in the art to which it appertains to make and use the same.

My invention relates to a combined portable burglar alarm and lock.

The object of the invention is to provide a simple and efficient device which may be easily carried in the pocket and which is adapted to be applied to doors and windows so as to effectively lock the same and adapted to be sounded so as to give an audible notification when any attempt is made to force open the door or window to which it may be applied, the invention being thereby especially adapted for use by commercial travelers and other persons carrying large and valuable stock and who are obliged, by reason of their vocation, to occupy rooms which are frequently without locks or with inefficient locks.

For a better comprehension of the invention attention is directed to the accompanying drawings, forming a part of this specification and in which—

Figure 1 is a vertical longitudinal section, showing the device as applied to a door and locked, and Fig. 2 is a top view of the same.

In both of the above views corresponding parts are designated by the same letters of reference.

The base *a* of the device is made of metal either cast or stamped out of a sheet in any suitable way and it is formed at one end into a long narrow shank *a'* inclining toward its forward end and adapted to be inserted between the edge of the door and its frame or between the two window sashes and with a rounded portion *a²* for the reception of the small alarm bell *a³*. This alarm bell is to be of any suitable construction so long as it possesses certain characteristics viz., that its clock work mechanism may be wound up and locked and that this clock work mechan-

ism may be started so as to give a single alarm stroke or a series of quick successive strokes. Bells of this variety are now used in many connections, such as for burglar alarms, bicycle alarms and for imitation electric bells. 55 Mounted upon this base *a* is an arm *b* adapted to be moved horizontally when desired within the bearings *b'* and *b²* which are made either integral with the base *a* or separated therefrom and attached thereto in any strong 60 and substantial manner. One end of this arm *b* is formed into a heavy enlarged finger *b³* with which the door or window will engage if an attempt is made to open the same. The other end of this arm *b* is formed into a stud *b⁴* 65 adapted to engage with and trip the bell mechanism. The arm *b* is normally held out of engagement with the bell mechanism by means of a small spiral spring *c* encircling the same and mounted between the bearing 70 *b²* and a pin, stud or collar *c'* on the arm *b*. On the extreme end of the shank *a'* is formed a sharp pointed stud or tooth *c²* adapted to engage into the door casing or window sash when the device is turned in the position 75 shown in Fig. 1.

Shoulders *d*, *d*, are formed in the base *a*, the object of which is to prevent the main portion of the base from following the shank *a'* into the space between the door and the casing 80 thereof, or between the two window sashes.

The operation of this invention is as follows: The device is held in the position shown in Fig. 2 with the bell in the horizontal position and the shank *a'* is introduced into the 85 space between the door and the casing thereof, or between the two window sashes, either by first closing the door or window and then forcing the shank into place or preferably by first bringing the door or window to an almost 90 closed position, then holding the shank *a'* against the edge of the door or window and with one of the shoulders *d* against the edge, and finally closing the door or window while holding the device in that position. The shank 95 *a'* being thus introduced into the crack between the door and its casing or between the two window sashes, is given a quarter turn whereby the stud or tooth *c²* will engage into the casing or sash, and the finger *b³* will be 100

turned over so as to face the edge of the door or moving part of the window. When an attempt is made to open the door or window it will engage with the finger b^3 which tends to 5 move the arm b toward the bell and trip the bell mechanism which will then sound and give an audible notification of the fact that the door or window is being tampered with. When the finger b^3 is moved a short distance 10 toward the bell it will come in engagement with the bearing b' and further movement thereof will be arrested so that an effective lock will be provided preventing any further movement of the door or window.

15 Having now described my invention, what I claim as new therein, and desire to secure by Letters Patent, is as follows:

20 A combined lock and alarm, consisting of the base a provided with a shank a' adapted to be introduced into the space between the

door and its casing and to be turned, whereby a stud or tooth c' on its shank will engage with said casing; an alarm bell a^3 secured to said base and having alarm mechanism therein; an arm b mounted on said base, in 25 bearings b' b^2 and adapted to engage with at one end and trip the bell mechanism; a spring c for holding said arm normally out of engagement with said bell mechanism; and a finger b^3 on said arm b in the path of the door, 30 adapted to move said arm b and trip the bell mechanism when the door is opened and to engage with the bearing b' so as to lock the door, substantially as described.

In testimony whereof I affix my signature in presence of two witnesses.

SIM C. LAWLOR.
